UNITED STATES PATENT OFFICE.

EDWARD L. MILLER, OF PHILADELPHIA, PENNSYLVANIA.

PAPER-CUTTING MACHINE.

SPECIFICATION forming part of Letters Patent No. 242,551, dated June 7, 1881.

Application filed April 11, 1881. (No model.)

To all whom it may concern:

Be it known that I, EDWARD L. MILLER, of the city of Philadelphia and State of Pennsylvania, have invented certain Improvements in 5 Paper-Cutting Machines, of which the following is a specification.

Paper-cutting machines in general consist of a knife to cut the paper moved by proper mechanism, a clamping-bar to hold the paper 10 in place while it is cut, and a gage by which the proper position of the paper is determined.

It is desirable that the clamping-bar shall be wide at its base, so as to take a firm hold 15 of the paper without wrinkling or disturbing it, as it will do, more or less, if narrow; but at the same time, with a wide clamping-bar, it is impossible to make the narrow cuts which are frequently necessary, because the width of the paper to be cut is determined by the distance 20 between the knife and the gage, and the clamping-bar intervenes between these two. It is to relieve this difficulty, which has not been done heretofore except by the use of complex devices, and to secure in one machine, without 25 complication of parts, the advantage of a wide bearing and the capacity of a narrow cut without reduction of thickness of the paper, that I have constructed the device represented in the drawings, in which—

30 Figure 1 is a back view of a paper-cutter, omitting the knife, which is shown in Fig. 3, but showing the gage A and the clamping-bar B, in which is a recess for the removable piece C, shown separate in Fig. 2.

35 In making narrow cuts the machine is used as shown in Fig. 1, but in ordinary work it is used as shown in section in Fig. 3, in which

the removable piece C is shown in its place in the clamping-bar B, forming with it a broad base to hold the paper firmly while it is cut, 40 the lift of the bar and the capacity to receive a thickness of paper being the same in either case.

It will be observed that the clamping-bar is constructed as the same part of similar machines has been heretofore ordinarily constructed, with the exception that it partly consists of or contains the removable piece C, which may be placed in a recess in the clamping-bar, as shown, or may be held in place upon its flat surface, in which case the entire clamping-bar is made narrow, with projections to support the movable piece. With this piece in place the clamping-bar holds the paper firmly with a broad surface, but the machine is not capable 45 of cutting paper of a width less than that of the whole bar; but when this piece is removed the gage may be brought up toward the knife, and the paper may be cut of a much less width, 50 and these results are attained by the removal 55 or replacement of this single piece from or upon the clamping-bar, with no change in any other part of the machine, and with no diminution of capacity as to thickness of paper to be held and cut. 60

65 I claim as my invention—

In combination with the knife and gage of a paper-cutting machine, the clamping-bar furnished with the removable piece C, substantially as and for the purpose specified.

EDWARD L. MILLER.
